UNITED STATES PATENT OFFICE.

FRANK C. SNYDER, OF SCOTTDALE, PENNSYLVANIA.

BUTTON-SETTING MACHINE.

1,329,438.

Specification of Letters Patent.

Patented Feb. 3, 1920.

Application filed October 14, 1916, Serial No. 125,548. Renewed June 26, 1919. Serial No. 307,016.

To all whom it may concern:

Be it known that I, FRANK C. SNYDER, a citizen of the United States, residing at Scottdale, in the county of Westmoreland 5 and State of Pennsylvania, have invented certain new and useful Improvements in Button-Setting Machines, of which the following is a specification.

This invention relates to button setting 10 machines, and resides in certain details of construction of the button feed and staple forming and setting mechanism conducive to economy in manufacture of the machine.

One feature of the invention is the use of 15 a two part swinging hammer with a novel connecting mechanism and retracting anvil. This construction simplifies the guides and actuating mechanism and provides a strong durable setting head which will thread the 20 buttons with the staple wire, cut and form the staples from a continuous length of wire and set the staples. The principal parts are all mounted on a single pivot and guide each other, while the number of small parts, 25 springs, &c., is reduced to a minimum.

Other features of invention relate to details of construction and will be apparent from a description of the invention as embodied in the button setter illustrated in the 30 accompanying drawings. In the drawings:—

Figure 1 is a side elevation of the complete machine, parts of the casing and frame being broken away to show the operating parts;

Fig. 2 is a front elevation of the upper part of the machine;

Fig. 3 is a section through the wire guide showing the wire feeding arm;

Fig. 4 is a side elevation of the same;

Fig. 5 is a perspective view of the wire-gripping face on the wire-gripping arm;

Fig. 6 is a section through the button box showing the spring-held door;

Fig. 7 is a perspective view of the top of 45 the button magazine with its guides;

Fig. 8 is a detail view of the button-feeding arm;

Figs. 9, 10 and 11 are fragmentary front elevations of the button-setting head showing successive steps in the forming and setting of the staple; and

Fig. 12 is a side view partly in section of the setting head parts in the position of Fig. 9.

55 The machine is carried on a hollow pedestal 15 which commonly would be of cast

iron, and this pedestal incloses an actuating pull rod 16 connected to an actuating treadle 17 held normally in its upper position by a coil spring 18.

On the top of the pedestal 15 is the main housing 19 of the setting head. This housing is hollow and open at its front face to expose the rivet forming and setting hammers 20 and 21 which are pivoted on a journal pin 22 common to the two, the setting hammer 21 being housed in a slot in the forming hammer 20. These two hammers 20 and 21 coact with a fixed anvil 23 having an inserted clenching face 24 formed as shown 60 clearly in Figs. 9 to 11, so as to clench the end of the staples toward each other in the usual manner.

The hammer 21 carries a depending plate or lug 25 which is connected at 26 by a pivot 65 to the actuating pull rod 16. At the beginning of downward motion the hammer 20 is latched to the hammer 21 by a latch 27 which is pivoted at 28 to the lug 25 and is held by a spring 29 behind a shoulder 30 70 on the hammer 20. The two hammers thus move together until the hammer 20 contacts with the work on the anvil 23. At this moment the tail or cam 31 on latch 27 strikes stop pin 32 and is tripped, thus releasing 75 hammer 21 for further movement.

The lug 25 is formed with a cam slot 33 through which passes a pin 34 on the end of a sliding forming anvil 35. This is mounted for longitudinal movement in a 80 guide 36, and is retracted by the cam 33 shortly after the hammer 20 has passed it to cut and form into a staple a length of wire 37 fed through guide 38 in housing 19.

The wire is drawn from a spool 39, rotatably mounted at the back of the machine, by a serrated clutching face 40 on a feed arm 41. The arm 41 is pivoted at 42 and its clutching face 40 engages the wire while the latter is held by a guide tube 43 which leads 90 to the guide 38. The guide tube 43 is cut away at 44 to permit the clutching face 40 to engage the wire and the necessary pressure is secured by the resilience of the parts. The arm 41 is fast to a second arm 45 and 95 is held in its forward position by a spring 46. When treadle 17 is depressed it draws down rod 16 and a stop 47 carried thereby strikes arm 45 and draws it back until it is caught by a weighted latch 48. The feed 100 arm 41 is thus retracted and set for action during the operative or downward stroke of

the hammers 20 and 21. When the treadle is released and has moved nearly to the limit of its upward motion, a stop 49 on rod 16 trips latch 48 and releases arm 45. 5 The feed arm then snaps forward under the action of spring 46 feeding the wire 37 through tube 43 and guide 38 across the open front of housing 19.

The wire passes just over the top of the 10 forming anvil 35 and through the shank or loop 50 of a button 51, held thereon by feed finger 52. The anvil 35 has a slot 53 to assist in retaining the button shank and the setting hammer 21 has a similar slot 54. 15 The forward feed of the wire is arrested by the collision of the end of the wire with the housing 19 at the opposite side of the slot in which the hammers 20 and 21 swing, the front of the housing 19 having an opening 20 or slot for the hammers as already stated.

The forming hammer 20 has slots 55 which engage and retain the wire 37 as the hammer descends, the hammer serving to shear off the length of wire projecting beyond guide 38 as its lower face passes this guide. At the moment of shearing this short length of wire is held over forming anvil 35 by the slots 55. On the continued downward movement of hammer 20 the 25 ends of the length of wire are wiped down over anvil 35 to form a staple, and are then held by the forming guide slots 56 in hammer 20 (see Fig. 10).

The button magazine consists of a box 57 30 removably mounted on top of housing 19 by means of headed lugs 58 which enter key-hole slots 59 in the bottom of box 57. Its approximately sector form is clearly shown in the drawings. At its lower corner it has 35 a door 60 held closed against the weight of the contained buttons by a spring hinge 61. The door 60 projects beyond the curved edge of box 57 and is struck open by the transfer cup 62 to discharge buttons from the box 57 into the cup, to fill the latter. 40 The cup 62 is mounted on an arm 63 which is pivoted at 64, about which point the arc of the curved side of box 57 is struck, and has a pin and slot connection 65 with hammer 20. This connection is such that when 45 the hammer 20 is swung down cup 62 swings down and receives a charge of buttons from the magazine. When hammer 20 swings up, the cup 62 also swings up, traveling along the curved side of box 57 and finally discharges its buttons into the open top of the box.

The buttons so discharged fall over a narrow guide plate 66 having a longitudinal slot 67. Certain of the buttons will be 50 caught by the guide plate with their shanks in the slot, and the remainder will fall down into the box or magazine 57. The 55 buttons so caught will slide down the guide plate until arrested by the impositive spring 60

finger stops 68 which engage and hold the foremost button of the series in the slot 67.

Successive foremost buttons of the series in the slot are caught and fed to the anvil 35, one at each actuation of the machine, 70 by the feed finger 52. This has a recessed end to engage the button head and is pivoted to an arm 69. A spring 70 urges the feed finger 52 against the button heads. The arm 69 is pivoted at 71 to housing 19 75 and has a pin and slot connection 72 with hammer 20 so arranged that finger 52 moves upward to get a fresh button as hammers 20 and 21 move down. On the reverse movement the finger 52 draws a fresh button 80 through stops 68 and brings it to position just as anvil 35 is projected to its outward position to support the button, and just as stop 49 trips latch 48 to feed the wire. The wire is thus fed through the shank or loop 85 of the button just as it comes into position. A slotted plate guide 73 forms a continuation of guide 66 below stops 68 and is carried on housing 19.

Starting with the parts in normal position the operation is as follows:—

Both hammers are up, a button is on anvil 35 and is held by finger 52 and the wire has threaded through its shank. The article to which the button is to be stapled is placed 95 on anvil 23. The treadle 17 is suddenly pushed downward its full stroke and then allowed to return.

On the down stroke cup 62 swings down, 100 opens door 60 and receives a charge of buttons. At the same time finger 52 is moved up and engages the foremost button in guide 66. Hammers 20 and 21 start down together, hammer 20 shearing off the staple length of wire threaded through button 105 shank 50 and then forming it into a staple by bending it over anvil 35. As the face of hammer 21 reaches anvil 35 this is retracted and the two hammers continue to move together until hammer 20 contacts with the 110 work on the anvil 23. At this point latch 27 is tripped and hammer 21 descends independently of hammer 20, forces the staple through the sheet of material to which the button is to be attached and clenches it 115 against the clenching surface 24.

On the up stroke the hammer 21 rises independently until it picks up hammer 20 when both hammers move together to their upper positions. As hammer 20 rises cup 62 120 swings up and discharges its buttons and arm 69 swings down and places a button on anvil 35 just after this is projected to its forward position. At the final limit of motion latch 48 is tripped and the wire feed 125 is actuated.

To change the style of button the magazine is slid diagonally upward and forward to release it when it is lifted off and another substituted. A simple actuation of the 130

machine without inserting the work will dispose of the button in position on anvil 35.

Various modifications obviously are possible, and the actuating mechanism and wire feed in particular are shown for illustrative purposes alone and their form is immaterial.

- Having thus described my invention, what I claim is:—
- 10 1. In a button setting machine, the combination of a staple-forming hammer and a staple-setting hammer, the setting hammer being movably housed within the forming hammer; a fixed pivotal support common to both hammers and about which they swing in a coincident path; a clenching anvil; and means for serially actuating said hammers in a continuous movement in one direction to first produce the staple and then clench the same.

2. In a button setting machine, the combination of a staple-forming hammer and a staple-setting hammer, the setting hammer being movably housed within the forming hammer; a pivotal support common to both hammers; a movable forming-anvil for coacting with the forming hammer; means actuated by the setting hammer for retracting said anvil out of the path of the setting hammer; a clenching anvil; and means for serially actuating said hammers.

3. In a button setting machine, the combination of a staple-forming hammer and a staple-setting hammer, the setting hammer being movably housed within the forming hammer; a pivotal support common to both hammers; a movable forming-anvil for coacting with the forming hammer; a cam formed on the setting hammer and engaging said anvil to retract the latter out of the path of the setting hammer as the latter descends; a clenching anvil; and means for serially actuating said hammers.

4. In a button setting machine, the combination of a staple-forming hammer and a staple-setting hammer, the setting hammer being movably housed within the forming hammer; a pivotal support common to both hammers; a clenching anvil; a latch for connecting said hammers to cause them to move together; and a stop for releasing said latch at a definite point in the descent of the hammers.

5. In a button setting machine, the combination of a staple-forming hammer and a staple-setting hammer, the setting hammer being movably housed within the forming hammer; a pivotal support common to both hammers; a movable forming anvil for coacting with the forming hammer; means actuated by the setting hammer for retracting said anvil out of the path of the setting hammer; a clenching anvil; a latch for connecting said hammers to cause them to move together; and a stop for releasing said latch

at a definite point in the descent of the hammers.

6. In a button setting machine, the combination of a staple-forming hammer and a staple-setting hammer, the setting hammer being movably housed within the forming hammer; a pivotal support common to both hammers; a movable forming anvil for coacting with the forming hammer; a cam formed on the setting hammer and engaging said anvil to retract the latter out of the path of the setting hammer as the latter descends; a clenching anvil; a latch for connecting said hammers to cause them to move together; and a stop for releasing said latch at a definite point in the descent of the hammers.

7. In a button setting machine, the combination of a staple-forming hammer and a staple-setting hammer pivoted at a common point; a latch mechanism for latching said hammers together to cause them to move in unison; means operated by the movement of the hammers for releasing said latch to permit the independent movement of the staple-setting hammer; a forming anvil with which said forming hammer coacts to form a staple; a cam moving with said hammers, and operative upon said anvil to retract the latter out of the path of the setting hammer; a clenching anvil; and means for feeding staple-forming wire to said staple-forming hammer.

8. In a button setting machine, the combination of a staple-forming hammer and a staple-setting hammer pivoted at a common point; a latch mechanism for latching said hammers together to cause them to move in unison; means operated by the movement of said hammers for releasing said latch to permit the independent movement of the staple setting hammer; a forming anvil with which said forming hammer coacts to form a staple; a cam formed on the setting hammer and operating upon the said anvil to retract the latter out of the path of the setting hammer; a clenching anvil; and means for feeding wire to said staple-forming hammer.

9. In a button setting machine, the combination of a staple-forming hammer and a staple-setting hammer pivoted at a common point; a latch for connecting said hammers to cause them to move in unison; a stop for engaging said latch to release the same at a definite point in the movement of said hammers; a staple forming anvil movably mounted and adapted to coact with the staple forming hammer; means actuated by the movement of the hammer for retracting said anvil out of the path of the setting hammer; and a clenching anvil for coacting with said clenching hammer.

10. In a button setting machine, the combination of a staple-forming hammer and

a staple-setting hammer pivoted at a common point; a latch for connecting said hammers to cause them to move in unison; a stop for engaging said latch at a definite point to release the same; a movably mounted forming anvil adapted to coact with the staple-forming hammer; a cam formed on

the staple-setting hammer and acting upon said anvil to retract the same out of the path of the setting hammer; and a clenching anvil 10 coacting with the clenching hammer.

In testimony whereof I have signed my name to this specification.

FRANK C. SNYDER.
